UNITED STATES PATENT OFFICE

VIOLET D. STEINEMANN, OF LOS ANGELES, CALIFORNIA

DESIGN FOR A DOLL

Application filed February 3, 1930. Serial No. 34,387. Term of patent 3½ years.

To all whom it may concern:

Be it known that I, VIOLET D. STEINEMANN, a citizen of the United States, residing at Los Angeles, in the county of Los Angeles and State of California, have invented a new, original, and ornamental Design for Doll, of which the following is a specification, reference being had to the accompanying drawing, forming a part hereof.

Fig. 1 is a front perspective of a doll embodying my invention.

Fig. 2 is a side elevation of the doll.

I claim:

The ornamental design for a doll as shown. In testimony whereof I have affixed my signature.
